No. 706,898.

Patented Aug. 12, 1902.

G. W. BURTON.

BRAKE FOR VEHICLES.

(Application filed Sept. 18, 1901.)

(No Model.)

UNITED STATES PATENT OFFICE.

GEORGE W. BURTON, OF MOREHEAD, KENTUCKY.

BRAKE FOR VEHICLES.

SPECIFICATION forming part of Letters Patent No. 706,898, dated August 12, 1902.

Application filed September 13, 1901. Serial No. 75,310. (No model.)

To all whom it may concern:

Be it known that I, GEORGE W. BURTON, a citizen of the United States, and a resident of Morehead, in the county of Rowan and State 5 of Kentucky, have made a certain new and useful Invention in Brakes for Vehicles; and I declare the following to be a full, clear, and exact description of the same, such as will enable others skilled in the art to which it 10 appertains to make and use the invention, reference being had to the accompanying drawings, and to letters of reference marked thereon, which form a part of this specification.

15. Figure 1 is a bottom plan view of my brake as applied. Fig. 2 is a section on the line 2 2, Fig. 1. Fig. 3 is a section on the line 3 3, Fig. 2.

The invention relates to brakes for wagons 20 and other vehicles; and it consists in the novel constructions and combinations hereinafter set forth and claimed.

In the accompanying drawings, C designates the wagon-reach, seated in bearings D D'. 25 Below the level of the seats there are provided on the bottom of the rear hounds the bracing transverse abutment-bars E E', which are parallel to each other and are secured to the rear hounds by suitable bolts e e and by the longitudinal straps or brace-bars F F', which extend parallel to the hounds and under the same on each side from the front transverse bar E' to the axle-bar A. Journal-seats G G are provided under the rear hounds between 30 the same and the straps or bars F F' to receive the journal portions of the transverse double-crank reel-shaft H. This shaft is provided with an eye-lug b in its middle portion, to which is connected the brake-chain k, which 35 40 when the brake is put in action by means of handle-bars connected to the crank ends a a of the reel-shaft is wound upon said shaft, applying the brake.

The transverse brake-beam is indicated at 45 L. To the ends of this bar are attached brake-shoes of any suitable character. The middle portion of the top of this brake-bar is provided with a flanged or grooved metallic plate l, the lateral flanges l' l' of which engage the sides of the reach C in a sufficiently loose manner to allow the brake-bar to move back and forward, while lateral movement is

prevented. The brake-bar is thereby held in centralized position.

The back of the brake-bar along its middle 55 portion is provided with a wear-plate m, against which work the ends of the curved plate-spring N, which is secured to the rear transverse bar E and serves to hold the brake-bar in its forward or free position against the 60 front transverse bar E'.

The ends of the spring N bear against the end portions of the brake-beam, whereby the action of the end portions of the beam is equalized.

65 The bottom of the brake-bar is also provided with a wear-plate P, having the middle lugs p p, which are perforated to receive the eyebolt R, having a nut r on its forward end, which is threaded sufficiently to provide for 70 some adjustment in regard to the chain should it be necessary. The brake-chain S is connected by one end to the eye-lug b of the reel-shaft and by its other end to the eyebolt R.

The brake-beam is held in normal position 75 by means of the spring device N. When the winding-shaft is turned by pressing one of the brake-handles, the chain is wound centrally on the reel-shaft, the brake-bar is drawn back in the slideway z between the hounds 80 and the strap-bars below them, and the brake-shoes are brought against the wheels. When pressure is taken off the brake-handles, the spring device moves the brake-bar forward, releasing the brakes.

85 The slideways, the transverse bars, the brake-bar, the spring device, and the reel-shaft are all in the same plane just below the hounds, and therefore the improvement is of 90 simple and economical character.

The brake-beam is limited in backward movement by the rear bar E, the plate-spring N being in this case straightened out against said bar.

Having described this invention, what I 95 claim, and desire to secure by Letters Patent, is—

In a vehicle-brake, the combination with the rear hounds, the two bracing transverse bars thereof, and the braces connecting said bars, and forming guideways between the same and the hounds, of the brake-beam having movement in said guideways, its grooved plate upon one side thereof, and engaging

the wagon tongue or pole for prevention of lateral movement, the perforated lugs upon the opposite side of said beam centrally of the length thereof, the curved plate-spring 5 having a bearing at its middle portion against one of said transverse bars, to which it is secured, and at its ends against the end portions of the brake-beam to equalize the application thereof, the transverse winding-shaft, 10 its bearings supported by said hounds, and the chain connected by one end to said shaft

at about the central portion thereof, and the adjustable screw connection with said lugs at its opposite end portion, substantially as specified.

In testimony whereof I affix my signature in presence of two witnesses.

GEORGE W. BURTON.

Witnesses:

A. W. VINTON,
W. C. REEVES.
